(57) **CLAIM**

The ornamental design for a lighting assembly, as shown and
described.

DESCRIPTION

FIG. 1 is a front, left isometric view of the lighting assembly,
in accordance with a preferred embodiment of my design;
FIG. 2 is a rear, right isometric view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the figures are directed to environment
and form no part of the claimed design.

1 Claim, 5 Drawing Sheets
